UNITED STATES PATENT OFFICE.

HOWARD M. BARBER, OF STONINGTON, CONNECTICUT, ASSIGNOR TO C. B. COTTERELL & SONS COMPANY, OF NEW YORK, N. Y., A CORPORATION OF DELAWARE.

MEANS FOR AND METHOD OF APPLYING ANTIOFFSET MATERIAL TO FRESHLY-PRINTED SHEETS.

Application filed February 20, 1922. Serial No. 537,835.

To all whom it may concern:

Be it known that I, HOWARD M. BARBER, a citizen of the United States, and resident of Stonington, in the county of New London and State of Connecticut, have invented a new and useful Improvement in Means for and Methods of Applying Antioffset Material to Freshly-Printed Sheets, of which the following is a specification.

10 In the printing art it frequently happens that only a portion or portions of a freshly printed sheet requires the use of an anti-offsetting medium, as for instance where only a portion or portions of the sheet are 15 printed or where only a portion or portions of the sheet are heavily printed and the balance of the sheet lightly printed. Slip sheets must be substantially the size of the printed sheets and the slip sheets are not 20 only expensive but require complicated machinery for properly introducing them between and separating them from the printed sheets. Where anti-offset material has been used heretofore, it has been applied to the 25 entire sheet and not only results in a considerable expense, but also requires the use of complicated apparatus for removing the surplus material from the sheets.

The object of my invention therefore is 30 to provide a novel means for and method of treating freshly printed sheets especially color sheets, by applying an anti-offset material in liquid or powder form onto the back of the freshly printed sheet opposite a 35 predetermined portion or portions thereof, to prevent offset from the next adjacent sheet in the pile after delivery.

My invention includes means whereby the backs of the freshly printed sheets opposite 40 heavily printed portions thereof are treated with anti-offset material, leaving the portions opposite the lightly printed or unprinted portions of the sheet untreated.

My invention more particularly includes 45 providing a member with one or more relief portions corresponding in outline to and adapted to register with a predetermined heavily printed portion or portions of the freshly printed sheet, means being employed 50 for applying the anti-offset material in liquid or powder form to said relief portion or portions for transfer thereby onto the back of the sheet opposite said predetermined heavily printed portion or portions.

A practical embodiment of my invention is represented in the accompanying drawings, in which the invention is shown as applied to a multi-color rotary sheet printing press.

Fig. 1 represents a longitudinal vertical 60 central section through a portion of a multi-color printing press with my anti-offset material applying mechanism shown in connection therewith.

Fig. 2 represents an exaggerated detail 65 section of the anti-offset material applying mechanism.

Fig. 3 represents a plan view of a proof which may be used in connection with the anti-offset material applying cylinder. 70

The printing mechanism herein shown comprises an impression cylinder 1, around which are grouped four plate cylinders 2, 3, 4, 5. The impression cylinder is herein shown as having two impression surfaces 75 6 and 7 with their respective sheet carrying head grippers 8 and 9. The sheet feed cylinder 10 is provided with a set of head grippers 11 for feeding the sheets from any suitable source of supply to the impression cylinder. The printed sheet delivery reel 12 may be provided with a set of head grippers 13 for taking the freshly printed sheets 80 from the impression cylinder and delivering them to any suitable point. 85

The means which I have shown for applying anti-offset material either in liquid or powder form to the back of the freshly printed sheet opposite a predetermined portion or portions thereof, is herein shown as 90 a rotary cylinder 14, having one or more relief portions corresponding in outline to and in registry with predetermined heavily printed portion or portions of the freshly printed sheet, said cylinder 14 being arranged to apply the anti-offset material onto the back of the sheet opposite the predetermined heavily printed portion or portions 95 thereof while the freshly printed sheet is being delivered. Friction pulleys 15 are 100 placed opposite the longitudinal margins of the sheet for the purpose of holding the sheet against the cylinder 14 with a pressure sufficient to cause the anti-offset material to transfer from the relief portion or 105 portions of the cylinder 14 on the back of the sheet.

One way of providing the cylinder 14 with

a relief portion or portions would be to wrap the proof 16 around the cylinder 14 in proper register with respect to the freshly printed sheet and then build up the required portions

5 of the proof to form reliefs, such as 17 and 18, corresponding in outline to the portions of the freshly printed sheet to the back of which it is desired to apply the anti-offset material.

10 The anti-offset material in liquid or powder form is contained in a reservoir 19; rolls 20 and 21 being provided for transferring the anti-offset material from the reservoir to the relief portions 17, 18, on the cylinder 14 for transfer thereby onto the back

15 of the freshly printed sheet opposite the heavily printed portions thereof as the sheet passes from the delivery reel 12. The roll 21 is carried in adjustable bearings 22 so

20 that it may be set in proper adjustment to both the roll 20 and the relief form carried by the cylinder 14. It may be desirable to use a blade 23 for regulating the supply of the anti-offset material from the roll 20 to

25 the roll 21.

From the above description it will be seen that by the use of my invention I am enabled to apply anti-offset material in liquid or powder form to the back of the 30 freshly printed sheet opposite that portion or portions only which require treatment to prevent offset from the next adjacent sheet in the pile. This arrangement results in a considerable saving of the anti-offset material which is of great importance and also eliminates the necessity of utilizing complicated and expensive machinery for removing excess anti-offset material from the freshly printed sheet.

35 40 This invention is particularly well adapted for use in connection with color work where certain portions of the sheet are provided with much heavier application of the color than other portions thereof, the back 45 of the sheet opposite said heavier portions requiring treatment for preventing offset.

It is evident that various changes may be made in the construction, form and arrangement of the several parts without departing 50 from the spirit and scope of my invention, hence, I do not wish to limit myself to the particular embodiment herein shown and described, but

55 What I claim is:—

1. Sheet printing and delivery mechanisms, and means coacting with the delivery

mechanism for applying anti-offset material onto the back of the freshly printed sheet opposite a predetermined portion thereof.

60

2. Sheet printing and delivery mechanisms, and means coacting with the delivery mechanism for applying anti-offset material onto the back of the freshly printed sheet opposite a predetermined heavily 65 printed portion thereof.

65

3. Sheet printing and delivery mechanisms, a cylinder coacting with the delivery mechanism and having a relief portion corresponding in outline to that portion of the 70 sheet to which the anti-offset material is to be applied, and means for applying the anti-offset material onto said relief portion for transfer thereby onto the back of the sheet.

70

4. Sheet printing and delivery mechanisms, a cylinder coacting with the delivery mechanism and having a proof applied thereto in registry with the printed sheet, said proof having a relief portion corresponding in outline to that portion of the sheet to which the anti-offset material is to be applied, and means for applying the anti-offset material onto said relief portion for transfer thereby onto the back of the sheet.

75

5. The method of preventing offset from 80 a freshly printed sheet onto the next adjacent sheet of a pile consisting in applying anti-offset material onto the back of the freshly printed sheet opposite a predetermined printed portion thereof.

80

6. The method of preventing offset from 85 a freshly printed sheet onto the next adjacent sheet of a pile consisting in applying anti-offset material onto the back of the freshly printed sheet opposite a predetermined heavily printed portion thereof.

85

7. The method of preventing offset from 90 a freshly printed sheet onto the next adjacent sheet of a pile consisting in producing a member having a relief portion corresponding to and in registry with a predetermined portion of the sheet, applying anti-offset material to said relief portion, and transferring the anti-offset material from said relief portion onto the back of the freshly printed sheet opposite the portion that corresponds to the said relief portion.

90

In testimony that I claim the foregoing as my invention, I have signed my name this 17th day of February, A. D. 1922.

HOWARD M. BARBER.
